(57) **CLAIM**

The ornamental design for a display screen or portion thereof with graphical user interface, as shown and described.

DESCRIPTION

FIG. 1 is a front view of a display screen or portion thereof with graphical user interface, showing a first embodiment of the new design.

FIG. 2 is a front view of a second embodiment thereof.

FIG. 3 is a front view of a third embodiment thereof.

FIG. 4 is a front view of a fourth embodiment of a graphical user interface of a display screen or portion thereof.

FIG. 5 is a front view of a fourth embodiment of a graphical user interface of a display screen or portion thereof; and, FIG. 6 is a front view of a fourth embodiment of a graphical user interface of a display screen or portion thereof.

The broken line showing of the outer rectangle illustrates the display screen or portion thereof. The remaining broken lines illustrate portions of the graphical user interface. The broken lines form no part of the claimed design.
